UNITED STATES PATENT OFFICE.

CARL BRAMMING, OF CHICAGO, ILLINOIS, ASSIGNOR TO ACCESSORIES MANUFACTURING COMPANY, A CORPORATION OF ILLINOIS.

CONNECTOR FOR ELECTRIC CIRCUITS.

1,315,203.

Specification of Letters Patent.

Patented Sept. 9, 1919.

Application filed January 18, 1917, Serial No. 143,032. Renewed June 30, 1919. Serial No. 307,777.

To all whom it may concern:

Be it known that I, CARL BRAMMING, a citizen of the United States, and resident of Chicago, county of Cook, and State of Illinois, have invented certain new and useful Improvements in Connectors for Electric Circuits, of which the following is a specification and which are illustrated in the accompanying drawings, forming a part thereof.

The invention relates to a connector of the plug and socket type, and is shown in connection with a socket adapted to receive a plug or lamp base at one end and a plug or terminal carrier at the other.

The objects of the invention are to provide an improved form of bayonet joint lock to permit the terminal plug to be partially withdrawn for the purpose of opening the circuit, while still being held within the socket, and to provide improved means for firmly holding the plug in its partially withdrawn position.

Preferred forms of embodiment of the invention are hereinafter described and shown in the accompanying drawings, in which—

Figure 1 is a side elevation of a lamp equipped with the improved connector;

Fig. 2 is a side view of the connector removed from the lamp;

Fig. 3 is a sectional view on the line 3—3 of Fig. 2, the electric circuit being shown partly diagrammatically;

Fig. 4 is a view similar to Fig. 2, showing a modified form of construction;

Fig. 5 is a view similar to Fig. 3, showing a modified form of construction; and

Fig. 6 is a sectional view on the line 6—6 of Fig. 5.

Referring to Fig. 1, the socket element 10 is shown in connection with the body of a lamp 11, with which it is attached in the usual manner, although the device may be utilized in other situations, as on the dash or cowl of an automobile, in which case the plug 12 would be the attached element. The plug is provided with two pairs of oppositely disposed laterally projecting studs 13, 14, adapted to coöperate with the bayonet joint slots of the socket, the two members of each set being arranged substantially in line longitudinally of the plug.

The bayonet joint slots 15 in the socket element enter obliquely from the end of the

socket, as shown at 16, and at the inner end of the oblique portion are offset backwardly to form a shoulder 17 for engagement by the studs in alternation. The margin of the slot forming a continuation of the opposite side of the oblique portion, after extending inwardly a short distance, is curved backwardly to form a cam surface 18. As the plug is inserted the studs enter the slot, and as the forward stud 14 slides down the cam 18 the plug is turned sufficiently to bring the stud 13 in position for engagement with the shoulder 17. In order to shift the plug to its second or partially withdrawn position, it is turned slightly to the right to disengage the stud from the shoulder, and, being released, the spring mechanism, hereinafter described, within the socket forces it backwardly, the stud 13 passing outward through the oblique portion 16 of the slot, thereby turning the plug sufficiently to bring the stud 14 into line with the shoulder 17, with which it makes engagement.

In the construction shown in detail in Fig. 3, the socket 10 is provided substantially midway of its ends with a fixed plate or block 19 of insulating material, through which reciprocates a hollow contact element 20 adapted to coöperate with the plug contact. A second hollow contact 21 telescopedly interfits the contact 20, and a spring 22, housed within the two contacts and reacting between their outer ends, normally holds them in extended position.

An incandescent lamp 23 is shown as fitted within the socket and locked thereto by the ordinary form of bayonet joint, as represented at 24, the central contact 25 of the base of the lamp engaging the contact 21.

The plug 12 is recessed from its inner end, and for convenience of manufacture may consist of a piece of tubing with a block of insulating material 26 fitted in the outer end thereof. A terminal rod 27, located on the axis of the plug, is fixed within the block 26, its end extending preferably to the inner end of the plug, as shown. This terminal engages the contact 20, compressing the spring 22, and is held in engagement therewith by the engagement of the outer studs 13 with the shoulders 17 of the socket slots. An annular disk 28 slidingly fits within the shell of the plug 12 and upon the rod 27, and is urged toward the inner end of the

plug by a helical spring 29 encircling the rod 27 and reacting against the block 26. The end of the rod 27 is preferably slightly enlarged to form a shoulder to limit the outward movement of the disk 28.

A pair of fingers 31, 32, extend from the contact 20, being spread apart to permit the entry between them of the plug terminal, the ends of these fingers engaging the disk 28 and forcing it inwardly as the plug is inserted into the socket. Upon the release of the stud 13 from the shoulder 17 in the manner hereinbefore described, the plug is forced backwardly by the action of the spring 29, the pressure of which then holds the stud 14 in engagement with the shoulder 17. The outer end of the rod 27 is centrally bored to receive the leading-in wire 33, which may be secured by means of a screw 34 set through 20 the block 26 and entering the bore of the rod. The return circuit from the bulb 23 may be through the shell of its base and the wall of the socket, which is grounded, as indicated at 35.

25 In the construction illustrated in Figs. 5 and 6, all of the parts are the same as shown in Fig. 3, except that a single stud 36, 37, projects from each side of the plug, co-operating with a bayonet joint slot 38 of known form, provided with two shoulders 39, 40, spaced longitudinally of the socket, the one for holding the plug in its fully inserted and the other in its partially inserted position; a further deviation from the construction of Fig. 1 being the substitution, for the fingers 31, 32, of an abutment 41 for engagement with the disk 28 and taking the form of a tube seated upon the block 19 and secured thereto by means of fingers 42, 40 43, extending through the block and clenched at the farther side thereof. By this arrangement the abutment is insulated from the contact 20. This form of abutment is preferable to that shown in Fig. 3, and will, of course, co-operate with either of the forms of bayonet joint lock shown, as will also the form shown in Fig. 3.

When the plug is fully inserted the circuit is closed. When the plug is partially withdrawn the circuit is open. The device therefore serves the purpose not only of a connector but of a switch, and constitutes a very convenient means for connecting the leading-in wires to an automobile tail lamp, 55 to comply with the ordinances in force in some cities requiring the location of the switch for the tail lamp at the rear of the car.

While preferred forms of the invention 60 are shown, changes of detail may be made without departing from its scope.

I claim as my invention—

1. In a circuit connector, in combination, 65 a socket having bayonet joint slots, an internal fixed abutment, a yielding contact

70 housed in the abutment, and a member projecting from the abutment beyond the end of the terminal, a plug recessed at its inner end adapted to enter the socket and having lateral studs co-operating with the bayonet joint slots, a terminal bar fixed within the plug recess, a member slidably within the recess and adapted to engage the projecting member, and a spring urging the slidably member toward the end of the plug. 75

2. In a circuit connector, in combination, 80 a socket having bayonet joint slots, a block of non-conductive material fixed within the socket, a yielding contact mounted in and projecting from the block and located on the axis of the socket, a rigid abutment projecting from the block beyond the end of the terminal; a hollow plug interfitting the socket and having lateral studs co-operating with the bayonet joint slots, an annular 85 plate slidable within the plug chamber, a spring reacting between the plate and a fixed abutment in the plug, and a terminal bar on the axis of the plug and fixed in the outer end thereof and projecting through the annular plate. 90

3. In a circuit connector, in combination, 95 a socket having bayonet joint slots, each of such slots being extended inwardly beyond its stud-engaging shoulder, a plug interfitting the socket and having a pair of longitudinally spaced lateral studs for co-operating with each slot, and spring means for holding such studs alternatively in engagement with the slot shoulders. 100

4. In a circuit connector, in combination, 105 a socket having bayonet joint slots, each of such slots being extended inwardly beyond its stud-engaging shoulder, a plug interfitting the socket and having a pair of longitudinally spaced lateral studs for co-operating with each slot, co-operating terminals carried, respectively, by the socket and plug, a spring housed within the plug, a bearing plate adjacent the inner end of the plug and engaging the spring, and a fixed abutment in the socket engageable with the bearing plate, the spring and abutment co-operating to hold the studs adjacent the end of the plug in engagement with the bayonet joint 110 shoulder. 115

5. In a circuit connector, in combination, 120 a socket having bayonet joint slots, each slot entering obliquely from the socket end, the inner end of the slot being enlarged by a lateral extension backwardly from the oblique portion and the opposite wall of the inner portion of the slot being inwardly inclined; a plug interfitting the socket and having two pairs of longitudinally spaced 125 and aligned lateral studs co-operating with the bayonet joint slots, the studs of each pair being adapted to engage the slot shoulder in alternation. 130

a socket having bayonet joint slots, each slot entering obliquely from the socket end, the inner end of the slot being enlarged by a lateral extension backwardly from the oblique portion and the opposite wall of the inner portion of the slot being inwardly inclined; a plug interfitting the socket and

having two pairs of longitudinally spaced and aligned lateral studs coöoperating with the bayonet joint slots, the studs of each pair being adapted to engage the slot shoulder in alternation, and spring means for holding the plug in each of its positions.

CARL BRAMMING.
